UNITED STATES PATENT OFFICE.

ALBERT HENRY TIMMIS, OF HARROW, ENGLAND.

SORTING INTO LENGTHS OR DRAGGING BRISTLES, HAIR, AND THE LIKE.

1,347,921.

Specification of Letters Patent.

Patented July 27, 1920.

Application filed February 4, 1919. Serial No. 274,920.

To all whom it may concern:

Be it known that I, ALBERT HENRY TIMMIS, a citizen of the United States of America, residing at Fairmount, Harrow View, 5 Harrow, Middlesex, England, have invented new and useful Improvements in Sorting into Lengths or Dragging Bristles, Hair and the like, of which the following is a specification.

10 My invention relates to an improved method of, and means for dragging or sorting into lengths bristles, hair and the like, and has for its object to supersede the tedious method of sorting by hand.

15 According to my invention the bristles, hair or the like (hereinafter referred to as bristles) to be dragged or sorted are preferably first combed and prepared in the known manner and beaten solid on the flag

20 ends, so as to provide a bundle of bristles the root ends of which project unevenly in accordance with the varying lengths of the bristles or the like. The ends of the longest bristles, that is to say, those which project

25 farthest from the bundle are then subjected to pressure alternately on the opposite sides against a fixed or resisting surface so as to bend them to and fro, this alternating movement, owing to the fact that the bristles

30 are slightly tapering, having the effect of lifting or pulling the bristles so acted upon from the bundle. By this means, therefore, all the bristles between certain predetermined fixed limits in length can be

35 lifted or pulled from the bundle, and by repetition of the operation the bundle can be subdivided according to the varying lengths of bristles.

40 A suitable arrangement of apparatus for carrying out the invention comprises a sliding receptacle or holder for the bristles, combed and prepared as described, a pair of combs constituting a selecting device, one of which is fixed and the other of which

45 can be reciprocated relatively to the fixed comb by any suitable means, a pair of feed rollers between which the bristles when lifted to a certain extent are caught and the rotation of which pulls the said bristles

50 out of the bundle, and a traveling band on to which such bristles are delivered.

Means are also provided for adjusting the holder so as to bring a further series of bristles into a position such that they

55 can be dealt with by the selecting device.

In the accompanying drawing—

Figure 1 is a front view of my improved machine.

Fig. 2 is a plan of the same with a part removed, and

Fig. 3 is a section on the line 3—3, Fig. 1. ⁶⁰ *a* indicates the frame of the machine, and *b* the receptacle or holder for the bristles *b*¹, which holder, as shown, is in the form of a drawer adapted to be pushed into and removed from the frame, the said holder having in it a pusher or movable partition *c* for holding the bristles in position during the pulling operation.

This pusher has pressing against it a ⁷⁰ spring *d* which will move forward to keep the bristles in position as the bulk of the bundle decreases. The pressure of this spring can be adjusted by a set screw *e* passing through the front of the holder *b*. ⁷⁵

f, *g* indicate the combs of the selecting device, the former of which is fixed with relation to the frame, while the latter is adapted to slide upon it. The teeth of these combs are arranged at a slight distance ⁸⁰ from one another so that the movement of the upper comb will not cut or injure the bristles, and in practice the teeth of the lower comb projects slightly beyond those of the upper comb so that the bristles will ⁸⁵ enter between the lower comb before they come into contact with the upper comb.

With this arrangement it is to be understood that the bristles which project between the teeth of the lower comb sufficiently far to be acted upon by the upper comb, will be bent to and fro as the upper comb reciprocates, which bending will have the effect of lifting the bristles so acted upon in the bundle. ⁹⁰

In practice, the reciprocation of the upper comb *g* is advantageously effected in one direction by a cam *h* and in the reverse direction by a spring *i*; the cam, as shown, is provided with two projecting surfaces ¹⁰⁰ 100 which operate against a roller *k* on the comb to move it outward until the projection moves away from the roller when the spring *i* moves the comb in the reverse direction.

l, *l* are the rollers, which, when the bristles are raised to a certain extent, catch such raised bristles and pull them completely out of the bundle, the bristles as they rise between the rollers striking an inclined cover *m* (as indicated in Fig. 3) which ¹⁰⁵ 110

causes them to fall over on to a traveling apron or band *n*.

The shaft *l*¹ on which one of the rollers *l* is mounted constitutes the driving shaft of 5 the machine and is provided with a driving pulley *o*; and the said shaft also carries a spur wheel *p* which engages with a corresponding wheel *q* on the shaft of the other roller, thereby causing the two rollers to 10 move in unison. On the shaft *l*¹ is a bevel pinion *r* which engages a bevel wheel *s* on the shaft of one of the rollers over which the belt *n* travels.

As the bristles are removed, the holder *b* 15 must be gradually pushed forward beneath the combs until all the bristles which project sufficiently to be caught between the said combs are removed. When this has been done the holder is moved backwards and 20 the bottom *t* of the said holder is lifted to a certain extent to raise the bristles when the operation before described is repeated, and so on until the whole of the bristles in the bundle have been sorted.

25 As shown in the drawing, the bottom *t* is carried by four screws *u*, *u* adapted to rotate freely in lugs *v*, *v* on the drawer, and the lower screw threaded ends of which enter screw threaded lugs *w* on the said bottom.

Claims.

1. The method of sorting bristles and the like into lengths, consisting in arranging the bristles to be sorted into a bundle, beating 35 the said bristles solid on the flag ends and in then subjecting the butt ends of projecting bristles to alternate pressure on opposite sides for raising those bristles from the bundle.

40 2. Apparatus for sorting bristles and the like into lengths comprising a holder for a bundle of bristles which are supported therein on the flag ends, and a selecting device including a pair of combs through 45 which the projecting butt ends pass, one of

the said combs being held against movement, and means for reciprocating the other comb relatively to the stationary comb so as to exert pressure alternately on opposite sides of the bristles and so lift them from the 50 bundle.

3. Apparatus for sorting bristles and the like into lengths comprising a holder for a bundle of bristles which are supported therein on the flag ends, a selecting device 55 including a pair of combs through which the projecting butt ends pass, one of the said combs being held against movement and the other being mounted for reciprocation relatively thereto so as to exert pressure alternately on opposite sides of the bristles, and means for seizing the bristles lifted by the selecting device and withdrawing them 60 completely from the bundle.

4. Apparatus for sorting bristles and the like into lengths comprising a holder for a bundle of bristles which are supported therein on the flag ends, a selecting device including a pair of combs through which the 70 projecting butt ends pass, one of the said combs being held against movement, and the other being mounted for reciprocation relatively thereto so as to exert pressure alternately on opposite sides of the bristles, and means whereby the bristle holder can 75 be adjusted in position relatively to the selecting device.

5. Apparatus for sorting bristles and the like into lengths comprising a holder for a bundle of bristles which are supported 80 therein on the flag ends, a selecting device including a pair of combs through which the projecting butt ends pass, one of the said combs being held against movement and the other being mounted for reciprocation 85 relatively thereto so as to exert pressure alternately on opposite sides of the bristles, and means for raising the bristle holder.

ALBERT HENRY TIMMIS.
